DESIGN FOR A BUTTON

Application filed January 19, 1931. Serial No. 38,352. Term of patent 14 years.

To all whom it may concern:

Be it known that I, FORREST G. PURINTON, a citizen of the United States, residing at Waterbury, in the county of New Haven and State of Connecticut, have invented a new, original, and ornamental Design for Buttons, of which the following is a specification, reference being had to the accompanying drawing, forming part thereof, in which the lining represents contrasting colors.

Fig. 1 is a top plan view of my new design;

Fig. 2 is a side elevation of the same.

I claim:

The ornamental design for a button, as shown and described.

FORREST G. PURINTON.
